UNITED STATES PATENT OFFICE.

CHARLES A. KETTERER, OF EAST ST. LOUIS, ILLINOIS.

METHOD OF REFRIGERATION.

Original application filed August 9, 1920, Serial No. 402,175. Divided and this application filed July 27, 1922. Serial No. 577,864.

To all whom it may concern:

Be it known that I, CHARLES A. KETTERER, a citizen of the United States, and resident of the city of East St. Louis, county 5 of St. Clair, and State of Illinois, have invented certain new and useful Improvements in Methods of Refrigeration, of which the following is a specification containing a full, clear, and exact description, 10 reference being had to the accompanying drawings, forming a part hereof.

My invention relates to improvements in method of refrigeration, and has for its primary object a method whereby the 15 amount of moisture within the storage chamber of a refrigerator is regulated.

A further object is the method of refrigeration, wherein the refrigerator or rather the storage compartment is maintained at a low temperature, and at the 20 same time, the amount of moisture therein is so regulated that the articles contained in the storage chamber will not lose any appreciable amount of weight, due to drying out, nor will the moisture in the chamber be sufficient to cause sogginess due to 25 a preponderance of moisture in the storage chamber.

In the drawings,

Fig. 1 is a vertical longitudinal section of a refrigerator of my improved chilling means installed therein;

Fig. 2 is an enlarged fragmental section, showing a portion of the ice container and solution container, showing the means of providing for an overflow;

Fig. 3 is a similar view, showing one of the plugs in position;

Fig. 4 is a perspective view of one of the 40 plugs made use of;

Fig. 5 is a top plan view of one of the dampers.

In the construction of my device I employ a refrigerator having a chilling or 45 storage chamber 6, and a refrigerating chamber 7. The storage chamber is divided or separated from the chilling chamber by means of a splash apron 8, a reticulated wall 9, and a baffle 10. This baffle is situated beneath the top of the refrigerator so 50 as to provide a passage 11 for the free circulation of air.

Within the chilling chamber 7 is located a liquid container 12 and ice container 13.

These containers are secured to angle irons 55 14. The liquid container 12 is secured to the inside of the angle irons, while the ice container 13 is secured to the outside. The lower edge of the ice container 13, and the upper edge of the liquid container 12 terminate on the same horizontal plane, but are spaced apart by the angle irons 14, so as to form a passage 15. This allows for an overflow. The purpose of this overflow will be explained in detail later. Secured 60 within the ice container 13 and near its bottom edge are angle irons 16 upon which rests a reticulated bottom 17. The ice container 13 is provided with a lid 18. This lid has a plurality of openings 19 which are 65 provided with downwardly projecting lips 20, and above these openings and secured to the lid 18 are a plurality of dampers 23 which have formed therein graduated 70 openings 24. These dampers are also provided with an upturned portion 25, so that the dampers can be moved.

Extending through the liquid container 12 are a plurality of tubes 26 and 27. The tubes 27 being preferably located centrally 80 of the liquid container. These tubes have extending therethrough a rivet or pin 28, upon which rests a tube 29. These tubes extend only a short distance above the upper edge of the liquid container, and are 85 arranged concentric with the tubes 26 and 27. Located within the tubes 26 and resting on the pin 28 are tubes 30. These tubes are concentric with the tubes 26 and extend upward to the lid or cover 18, and are of 90 sufficient diameter to receive the lips 20. Located within the tube 27 is a tube 31. This tube is also concentric with the tubes 27 and 29, but terminates a short distance above the tube 29 and below the reticulated 95 bottom 17. Located within the liquid container 12 is a refrigerating coil 32. The ice container and liquid container as well as the angle irons 14 are located in the drip pan 33, which has an outlet 34 leading 100 to a sewer or to a tank for collecting the overflow of liquid.

The operation of my method is as follows:

The liquid container 12 is first filled to its uppermost edge with a non-freezing solution. The lid 18 is removed from the ice container and crushed ice placed therein. Mixed with this ice is a chemical which will

unite with the drippings, or with the melting ice, and form a non-freezing solution. This mixture of chemical and melting ice drips through the reticulated bottom 18 and into the liquid container 12. As these drops of non-freezing solution drip into the container 12 which is already full of non-freezing solution, the container is filled to overflowing and due to the constant dripping, the upper 10 surface of the liquid within the container 12 is agitated, so as to form waves. These waves spread in all directions, similar to when a pebble is dropped into a pool of water, and when reaching the edges of the 15 container 12 or of the tubes 26 and 27, they will flow or slop over and trickle over the surfaces. This trickling will cut off any frost which has gathered on these surfaces. The tubes 29 and 31 are kept clear in the 20 same manner.

When it is desirable to have frost gather on certain parts of the container 12, I make use of the plugs 35 which close portions of the passage way 15 between the containers 12 and 13, so that the container 12 may have frost on a portion thereof, while the other portion is kept clear of frost by the flow of non-freezing solution thereover. The non-freezing solution that does flow over is 25 caught by the drip pan 33 and passes out through the drain pipe 34. If I desire moist air to pass into the refrigerator, I open the valve which will permit air to flow into the ice container and close off the valves or 30 dampers over the pipes 30. In this way, the air after having passed over the ice in the ice container carries a certain amount of moisture with it, which will be distributed into the storage chamber 6, while if dry air 35 is desired, the dampers over the pipes or tubes 30 are opened and the central dampers which admit air directly to the ice chamber 40 are closed.

I may also achieve a mixture of air by 45 opening the dampers, both to the ice chamber and to the pipes 30, the amount of air passing therethrough being regulated by the graduated openings in the chamber. (See Fig. 5.)

It is also possible to supply a greater or 50 less amount of moisture by means of the plugs 35. These plugs serving to retain frost on a portion of the container 12. Where no frost is retained on the container 55 12, a dry air results in the storage chamber 6, inasmuch as any moisture given off by the food products contained therein has a tendency to condense on the chamber 12. This condensation is carried away by the overflow, while if frost is allowed to accumulate thereon, the frost will in time get so thick 60 as to prevent this condensation to a great extent and cause moist air to circulate through the storage chamber. In this way I prevent 65 the loss of weight due to the absorption of

the moisture contained within the food product put in the storage chamber, but at the same time can regulate the moisture within the chamber so as to prevent mildew forming, due to excess of moisture.

By means of the refrigerating coil 32, I can reduce the temperature of the refrigerator to a point considerably below that delivered by the ice in the ice container. In this way a small amount of crushed ice will last 75 a very long time. Its only purpose being to constantly supply the liquid container 12 with additional non-freezing solution, so that the amount of frost and consequently 80 the humidity of the storage chamber can be regulated.

I may also if found desirable, eliminate the ice chamber, and merely place a secondary liquid chamber or container above the container 12 and allow the liquid to slowly 85 drip from one chamber or container into the other, and accomplish the same purpose. In this case, however, the refrigerating coil 32 is absolutely essential, while when using crushed ice, the refrigerating coil tends to 90 reduce the temperature of the non-freezing solution and assists in cutting down the quantity of ice needed to keep the refrigerator at the proper temperature.

The tubes 26, 27, 29 and 31, are kept clear 95 of frost, and consequent clogging by permitting the non-freezing solution to overflow or drip therein. While the tubes 30 are kept 100 clear of frost due to the fact that the air passing therethrough is at a relatively higher temperature than the balance of the air, it being drawn from the upper part of the freezer, and is consequently at a high enough temperature to melt any accumulation 105 of frost on the inside of these tubes. The frost on the outside being removed by the non-freezing solution.

This is a division of my application for Letters Patent on refrigerators, filed August 9, 1920, under Serial No. 402,175.

Having fully described my invention, what I claim is:

1. The herein described method of refrigeration which consists in filling the liquid container of a refrigerator with non-freezing solution, cooling said solution by means of a refrigerant separate from said solution, and slowly adding additional non-freezing solution to the first mentioned solution.

2. The herein described method of refrigeration which consists in filling the liquid container of a refrigerator with a non-freezing solution, cooling said solution by means of a refrigerant, and continuously and slowly adding to said solution additional non-freezing solution, thus agitating the solution in the container and causing it to overflow the sides thereof to remove frost therefrom.

3. The herein described method of refriger-

eration which consists in filling the liquid container of a refrigerator with non-freezing solution, circulating a refrigerant through said solution, and continuously adding to said solution small amounts of an additional non-freezing solution, whereby said solution is caused to overflow the sides of the container and remove frost therefrom.

4. The herein described method of refrigeration which consists in filling the liquid container of a refrigerator with a non-freezing solution, cooling said solution by means of a refrigerant, slowly dropping into said solution additional non-freezing solution thus agitating the surface of the solution in

the container and causing it to overflow the sides thereof.

5. The herein described method of refrigeration which consists in filling the liquid container of a refrigerator with a non-freezing solution, cooling said solution by means of a refrigerant, slowly dropping into said solution additional non-freezing solution thus agitating the surface of the solution in the container and causing it to overflow the sides thereof at predetermined points.

In testimony whereof, I have signed my name to this specification.

CHARLES A. KETTERER.
